UNITED STATES PATENT OFFICE

2,439,238

SAFETY SOAP AND WASHCLOTH HANGER

Leon L. Collins, Savannah, Ga.

Application May 21, 1946, Serial No. 671,365

1 Claim. (Cl. 248—330)

1

This invention relates to hanger-type holders for soap, washcloths and the like, more particularly but without absolute limitation for use in connection with shower baths.

The prime object is to produce a device or utility of a character which possesses practical features of safety as well as convenience in manipulation and use of the same, and which can be hung in the immediate bathing area within easy reach of the bather and with safety and in avoidance of accidents and injuries which otherwise frequently occur to bathers due to the dropping of soap, washcloths and other articles, and slipping in reaching for soap, washcloths and the like as ordinarily and usually heretofore placed in definite side positions.

Another object is to produce a device or utility of a hanger-type embodying a spring-wound supporting spool or reel secured at an elevation and from which depends an extension cord normally wound on the spool or reel by the reactive unwinding action of the wound spring of the spool or reel, the cord carrying at its outer end a pocket or container for soap, washcloth or the like, and being graspable by the bather and drawn extensibly to the desired or necessary length for use of the contents of the pocket or container.

A further object is to produce a simple yet efficient and durable structure which is easily and inexpensively manufactured.

Other objects and advantages to be attained will hereinafter more fully appear in the following description.

A practical but non-limiting exemplification of the invention is illustrated in the accompanying drawings, wherein:

Figure 1 is a front elevation of the device of the invention, showing in side elevation a form of supporting bracket from which the device is hung;

Figure 2 is an end view of the cord holding and reeling portion of the device detached; and

Figure 3 is a detached view showing details of the spool or reel spindle and spring construction and arrangement.

Referring now to the drawings in detail, the numeral 5 designates generally a supporting bracket which is attached as at 6 to a representation 7 of an upright support or a side wall portion.

As shown, the bracket 5 is formed of heavy wire, comprising an upper horizontal bar 8 and a lower inclined bar 9, the inner end portions of said bars being respectively turned angularly, as at 10, 11, said end portions 10 and 11 being fitted hingedly in aligned vertical bores provided

2

therefor in a base bracket member 12, through which the aforesaid upright or wall attachment 6 is effected.

The forward end portions of the bracket bars 8 and 9 are brought together and formed with side-by-side registered loops as at 13. Intermediate the opposite ends of the bracket bars 8 and 9, the same are braced by a strut member 14.

Hingedly suspended and freely swingable on the bracket 5 is the main structural element of the device assembly of the invention to be now described.

As shown, this main element, designated generally by the numeral 15, comprises an open frame made of wire which is relatively stiff and form retentive but possessing a certain degree of inherent resiliency for a purpose to be later more fully described.

The main frame 15, which is formed from a single piece of wire, comprises a pair of parallel vertical side bars 16. Said bars 16 are cross-connected by an aligned counterpart pair of upper reversely and compoundedly angularly bent and curved, somewhat archedly connected bars 17, the meeting inner end portions of said bars 17 being twisted together, as at 18, producing an upstanding neck, and at the end of said neck portion 18, the parallel extreme end portions of the wire being formed into a pair of side-by-side registered loops 19.

The registered loops 19 are provided for use in suspendedly hanging the device of the present invention in the use thereof. As shown, the loops 19 are hingedly secured in the loop portion 13 of the supporting bracket 5. However, in some adaptations and uses of the device of the present invention, the loop portion 19 of the device may be obviously attached in a conventional manner directly to horizontal support of a suitable kind, as, for example, a ceiling.

The main frame 15 further comprises a pair of aligned lower bars 20 of similar shape as the aforesaid upper bars 17, but instead of being arched like said bars 17, the lower bars 20 are sagged where they meet at the middle thereof. The integral sagged middle connecting portion of the pair of lower bars 20 is looped, as at 21, with a twisted neck portion 22, and said loop 21 is turned substantially at right angles to the vertical plane of the frame (see Figure 2). The loop 21 is provided as a guide eye through which the elongated cord element 23 is threaded and guided in its lengthwise movement to and from a spool or reel element of the device, designated generally by the numeral 24.

The spool or reel 24 includes two right-angularly crossed open frames 25, 26, of generally oblong or substantially rectangular form except that instead of its longitudinal and end sides being straight throughout the extent thereof, the end sides are bowed outwardly, as at 27, and the longitudinal sides are undulated, as at 28 (see Figure 1).

The inner end of the cord element 23 is attached in any suitable manner to the spool or reel 24 and the cord is then coiled and wound upon and unwound from the spool or reel in the use of the device as will be presently described. As shown (see Figure 1) an aperture 29 is provided in at least one of the longitudinal sides of the spool or reel 24, into which aperture 29 the extreme inner end portion of the cord 23 is inserted before the cord is wound upon the spool or reel. Obviously, in the complete winding of the cord 23 on the spool or reel, there is a large multiplicity of coils thereabout, but to minimize the work of illustration and the possible unnecessary covering and obscuring of some of the structural features, only a few coils of the cord 23 on the spool or reel 24 are shown by way of example in Figure 1.

To the lower end of the cord element 23 is attached a pocket element or container 30 for soap, a washcloth or other essential or needed article to be used in taking a bath. No detail structural feature of the pocket or container 30 is illustrated as the same, of itself, is not a part of the present invention. Suffice it to say, that in the regular and more general use for which the device of the present invention is designed, the pocket or container element 30 is usually made of a suitable cloth or washable fabric and of any desirable size and form.

As shown, the pocket element or container 30 is provided with an attaching member 31, which is connected swivelly, as at 32, to a connector member 33, to which latter the lower end of the cord element 23 is securely fastened in any suitable or obvious manner.

In the use of the device of the present invention, the cord connector nipple-like element 33 may come in contact with guide eye 21 of the main frame 15 when the cord 23 is fully wound on the spool or reel 24, or in cases when a substantial length of the unwound cord is desired or necessary to be held extended below the guide eye 21, a knot 34 may be tied in the cord, as indicated in Figures 1 and 2. Obviously, this knot 34 is readily tied and untied, at will, by a user of the device.

The spool or reel 24 is detachably mounted in the main frame 15. As shown, the mounting includes an axle shaft 35. This shaft 35 extends from end to end of the main frame 15 and preferably with each end of the shaft extended a little beyond the vertical members 16 of the frame (see Figure 1). The opposite end portions of the axle shaft 35 are provided with open-ended longitudinal slots 36, which fit tightly on flattened middle portions 36' of the vertical end members 16 of the main frame 15. In applying and removing the axle shaft 35, the frame end members 16 are readily sprung outwardly from each other sufficiently to clear the ends of the shaft in moving the same into place and in dismounting it, the frame members, by their resiliency, springing back into normal position and into holding relation if the axle shaft 35 is in placed position. The axle shaft placed in position in the main

frame 15 is securely supported and held from turning.

As shown more clearly in Figure 3, the crossed end portions 24' of the spool or reel frames 25 and 26 are provided with longitudinally aligned apertures in which are fixedly fitted bearing bushings 37, which latter are sleeved rotatably on the stationary axle shaft 35. The spool or reel 24 is thus mounted freely rotatable on the shaft 10 35.

Fixedly secured to one of the bearing bushings 37 is a cupped element 38 that rotates with the spool or reel 24, while fixed on the axle shaft 35, adjacent its end opposite, that near to which 15 the cupped element 38 on the spool or reel 24 is located, is a collar 39, which latter, of course, is non-rotatable.

An elongated helical spring element 40 is coiled freely and loosely around the axle shaft 35, one 20 end 41 of the spring being secured to the annular flange of the cupped element 38 and the other end 42 of the spring being secured to the collar 39. In this way, rotation of the spool or reel 24 in one direction, say by pulling the cord element 23, the spring element 40 is wound, and by releasing the pulling hold on the cord element 23, the spring unwinds and reversely rotates the spool or reel 24, and cord element thereupon becomes rewound on the spool or reel.

30 A device of the character herein illustrated and described is easily installed and safely used in connection with a shower bath or place of use, particularly in large bath places in association with railroad shops, machine shops, and other 35 work places where bath facilities are necessarily provided for use by relatively large number of persons at the same time and the slippery condition of the floors of the bath place makes it rather hazardous for persons having to reach 40 here and there for soap, washcloths and the like, as usually heretofore placed in holders positioned in definite side positions. An important advantage in the use of the device of the present invention is due to the flexibility and extensibility 45 thereof, with the provision at the lower end of the cord element of the pocket element or container for soap, washcloth or other essential articles used in bathing. So, too, the assembled working parts of the device are easily dismantled for repair and replacement.

50 The illustrated structure is but one practical exemplification of the invention. Hence, modification and change is contemplated within the spirit and scope of the appended claim. The 55 invention, therefore, is not limited to the specific construction and arrangement shown.

What is claimed is:

As an article of manufacture, a safety device 60 for supporting soap and bathing articles conveniently located for use in bathing which device comprises, in combination, an open frame of stiff, form-retentive, inherently resilient wire formed to provide a parallel pair of opposite vertical side bars, corresponding intermediate portions of said side bars being flattened, the ends of said wire being joined to form a hook to provide a central balancing means of supporting attachment at its top, said wire being formed to provide a guide eye at its bottom, a horizontal shaft having open-ended longitudinal slots in its opposite end portions, said slotted end portions of the shaft being slidably fitted tightly on said flattened frame side bar portions to be retained from rotation, a reel element comprising 65 a crossed pair of elongated substantially ob-

long open frames, the crossed opposite transverse end members of said reel frames being apertured in longitudinal alignment and axially of the reel, bearing bushings fitted in said axial end apertures of the reel element and freely rotatable on said shaft, an elongated helical spring surrounding said shaft and with its ends secured to said shaft and said reel respectively, an elongated cord element attached to and wound on said reel element and threaded through said guide eye, a swivel attached to the free end of said cord element, a mesh container attached to said swivel, means for limiting the retraction of said cord by said reel, and a bracket formed by wire bent to provide angularly disposed arms having inturned ends, a support for removably receiving said ends, and a link between said arms and slidably thereon to space them in selected angular relationship to be retained on said support or removed therefrom.
